CLAIM

(52) **U.S. Cl.**

The ornamental design for a writing instrument, as shown and described.

USPC **D19/50**

DESCRIPTION

(58) **Field of Classification Search**

FIG. 1 is a perspective view showing a new design for a writing instrument;

USPC D14/411; D19/35, 36, 41-51, 53-58;
24/11 F, 11 P, 11 R; 401/52, 99-109,
401/192, 195, 196

FIG. 2 is a front view of the writing instrument of FIG. 1;

See application file for complete search history.

FIG. 3 is a right side view of the writing instrument of FIG. 1;

(56) **References Cited**

FIG. 4 is a rear view of the writing instrument of FIG. 1;

U.S. PATENT DOCUMENTS

FIG. 5 is a left side view of the writing instrument of FIG. 1;

D240,525 S 7/1976 Delores
D245,504 S 8/1977 Defores
D254,912 S 5/1980 Ito
D280,420 S 9/1985 Verhaegue
D280,737 S 9/1985 Verhaegue
D323,189 S 1/1992 Tu
D323,852 S 2/1992 Gomez

FIG. 6 is a top plan view of the writing instrument of FIG. 1;

and,

FIG. 7 is a bottom plan view of the writing instrument of FIG. 1.

The broken lines in the drawings illustrate unclaimed portions of the writing instrument and form no part of the claimed design.
